THE WM. H. HORSTMANN COMPANY, OF SAME PLACE.

DESIGN FOR A SKIRT-PROTECTOR.

SPECIFICATION forming part of Design No. 28,795, dated June 7, 1898.

Application filed May 4, 1898. Serial No. 679,735. Term of patent 7 years.

To all whom it may concern:

Be it known that I, EMIL PIETSCHMANN, a citizen of the United States, residing in Philadelphia, Pennsylvania, have invented a new and original Design for a Skirt-Protector, of which the following is a specification.

My design is fully shown in the accompanying drawing, which represents a face view, on an enlarged scale, of a piece of the skirt-protector.

The design comprises the heading 1 and the fringe 2. The heading 1 has an upper edging 3 and immediately below the same a longitudinal rib formation 4, and the body 5 of the heading has a surface ornamentation consisting of rows of separated oblong fig-

ures 6, distinguished from the groundwork by difference of color or shade. The fringe has a narrow heading 7 and loose depending threads 9.

I claim—

The design for a skirt-protector substantially as described and as shown in the accompanying drawing.

In testimony whereof I have signed my name to this specification in the presence of two subscribing witnesses.

EMIL PIETSCHMANN.
